SHOE INSERT

Edward C. Meldman, Milwaukee, Wis.

Application December 7, 1946, Serial No. 714,753

1 Claim. (Cl. 36—71)

2

This invention relates to improvements in shoes and inserts for shoes, and more particularly to a novel interior construction of shoes.

Modern shoes are made in standard shapes and sizes to fit feet with normal function. In normal function body weight is properly distributed in the heel, shank and sole of the shoe. A serious problem results from the fact that a great many feet do not have normal function and fail to distribute body weight equitably in the shoe. Such feet are not necessarily sick feet but because they are structurally unstable, they lack adequate natural balance and support and cannot function in harmony with the shoe. An object of this invention is to control the unstable foot in a standard shoe, by helping to balance and support the foot thereby effecting a more equitable distribution of body weight in the shoe. The unstable foot requires more than normal muscle effort to maintain balance and support. Therefore, it tends to become prematurely fatigued. A further object of this invention in aiding the unstable foot to maintain its balance and support, is to retard the onset of muscle fatigue.

The unstable foot, especially when fatigued, tends to shift in the shoe. A distortion of the shoe results, the heels and soles wear unevenly and the shank of the shoe receives too little or too much of the body load. There is a constant conflict in function between the unstable foot and the shoe. This is an important factor in causing many common foot troubles. An object of this invention is to help prevent the unstable foot from developing many prevalent foot ailments caused by conflict with the shoe structure.

I have found that control of the unstable foot in the shoe requires more than so-called support of the arches. It requires dynamic control of the entire foot, that is in the standing phase, leverage phase and intermediate phases of foot function. While standing, the weight of the body is received in the foot by the ankle bone (talus). From there the load is distributed to the various underlying foot structures and transmitted to the heel, shank and sole of the shoe. Antero-posterior weight stresses normally flow from the talus, forward to the three inner metatarsals and backward to the heel bone. The vertical weight stresses are received from the talus directly by the sustentaculum tali, the obliquely slanted inner shelf of the heel bone. These vertical stresses flow, not directly forward, but downward and obliquely outward toward the cuboid and outer two metatarsal bones. The body's weight is thus divided in the foot into two distinct weight

transmission channels. The antero-posterior channel spans over the oblique channel in a manner similar to that of an overhead railroad track crossing over a road. Since the talus distributes the body's weight to the two transmission channels of the foot, sturdy support by the structures underlying the talus is important for efficient function. In the unstable foot, the structures underlying the talus fail to provide the normal sturdy foundation at this critical weight distribution center. This distorts the weight transmission channels. Vertical weight stresses which normally are deflected by the sustentaculum tali obliquely towards the shank of the shoe are instead usually forced directly forward and inward through the talus. Distorted function and strain ultimately causes further structural distortion and instability. An object of this invention is to deflect the vertical stresses in the unstable foot along the normal oblique transmission channel to the shank area of the shoe without interfering with the spring action of the first metatarsal segment. In any conventional so-called arch supports, now in use, such spring action is somewhat interfered with.

In normal walking the body progresses in a forward direction while simultaneously body weight is being shifted alternately from one foot to the other. The antero-posterior weight transmission channel of the foot normally is pointed straight ahead and transmits the forward weight forces. The oblique transmission channel carries the diagonal weight forces as body weight is shifted to it from the other foot. This weight flow curves forward upon reaching the cuboid, and as the heel is lifted for the leverage phase of the step, this weight flow is directed successively through the heads of the fifth, fourth and third metatarsals to the second and first metatarsal heads and toes. Here it merges with the forward weight flow for the take-off thrust toward the opposite foot. As the unstable foot receives the diagonal weight forces it tends to go off balance at the outer border of the forefoot. Only with more or less difficulty does it maintain its balance. In the leverage phase, extra effort also is needed to redirect the oblique weight force toward the take-off area in time for the propulsive thrust. This is the most common cause of the foot's over-riding of the outer insole border.

An object of this invention is to counter-balance the anterior outer border of the unstable foot and redirect the weight force toward the take-off area of the foot and shoe.

55 In the skeletal structure of the foot, a line

drawn from the heel bone through the fourth metatarsal bone represents a sturdy channel capable of great support. It is an object of this invention to utilize this natural advantage by having a convex elevation in the device which runs from the cuboid area along the shaft of the fourth metatarsal bone to afford better support for this important part of the foot by establishing direct weight transmission with the shank and sole area of the shoe for this part of the foot.

The shape and principle of the device is constant for all shoes except as varied to suit the style of shoe. In higher heel shoes the posterior thickness is reduced and sometimes eliminated. In low heel shoes the anterior thickness may be reduced. The examples shown are for the average shoe.

Other and further objects of the invention will be apparent as the description proceeds, reference being had to the accompanying drawing, in which:

Fig. 1 is a view in perspective of an improvement for shoes embodying my invention.

Fig. 2 is an inverted plan view of the same.

Fig. 3 is a view on lines 3—3 of Fig. 1.

Fig. 4 is a sectional view on line 4—4 of Fig. 1.

Fig. 5 is a view on line 5—5 of Fig. 1.

Fig. 6 is a view in perspective of the invention as embodied in an insert for shoes, showing the device proper in dotted lines.

Fig. 7 is a sectional view on line 7—7 of Fig. 6.

Fig. 8 is a plan view showing the device and its relative placement with reference to the bones of the foot and the shoe insole.

Fig. 9 is a view partly broken away in perspective showing the device in position in a lady's shoe.

Fig. 10 is a view in perspective of a man's shoe for the left foot with the device in position.

Fig. 11 is a vertical sectional view taken through a shoe and the wearer's foot.

It will be understood that the device may be incorporated within a shoe during the manufacture thereof. It may also be incorporated within an insert similar to an insole which may be inserted into a conventional shoe of standard make.

Referring more particularly to the drawing, the numeral 10 refers to the device generally as shown in Fig. 1, showing a unit of the invention which would be built into a shoe for the left foot. The left hand portion of the device has an upturned edge 11, which is curved to conform with the left side of the human foot. The base portion 12 of

the device has two rounded lateral edges at 13 and 14 thereof, and said edge portions of the device are not cushioned or padded. The base portion 12 is longitudinally thickened arcuately in cross section, with the apex of said padded portion extending longitudinally of said base 12, approximately one-third of the distance from the left edge of the left foot accommodating device. The vertical sectional views in Figs. 3, 4 and 5 show the approximate allocation of the thickened area.

Fig. 6 shows an insole adapted to be placed in a standard shoe, with the device of the present invention shown in dotted line in said structure. It will be seen that the upturned portion 11 is reduced upwardly padded as shown in Fig. 7.

In Fig. 8 the inverted plan view of the left foot shows the proper location and relation of the device to the bones of said foot. Adapted to a lady's shoe as shown in Fig. 9, the device is shown conforming to the peculiar shape of the shoe, and may have relatively less thickening toward the rear or posterior portion thereof, with an increase of thickening relatively in the anterior part.

It will be understood that the device is capable of many modifications in structure and design, without departing from the spirit of the invention, within the scope of the appended claim.

Having thus described my invention, what I claim and desire to secure by Letters Patent of the United States, is:

An addition to the standard shoe for stabilizing the foot, comprising a base portion terminating short of the front of the foot in a curved lobe, and having a curved lobe under the longitudinal arch at one side, a built up portion transversely arcuate in cross section with a convexity extending longitudinally thereof, and an upward flange at the other side adapted to engage about the outer edge of the foot.

EDWARD C. MELDMAN.
